Primary Examiner — Abraham Bahta(57) **CLAIM**

The ornamental design for a sauce pocket, as shown and described.

DESCRIPTION

FIG. 1 is a rear top left perspective view of a sauce pocket, showing my new design.

FIG. 2 is a rear bottom left perspective view thereof.

FIG. 3 is a front top right perspective view thereof.

FIG. 4 is a front bottom right perspective view thereof.

FIG. 5 is a front elevational view thereof.

FIG. 6 is a rear elevational view thereof.

FIG. 7 is a right elevational view thereof.

FIG. 8 is a left elevational view thereof.

FIG. 9 is a top plan view thereof; and,

FIG. 10 is a bottom plan view thereof.

The broken lines shown in the figures depict portions of the sauce pocket that form no part of the claimed design.

1 Claim, 10 Drawing Sheets(56)
